[57] CLAIM

We claim the ornamental design for the male electrical connector with overload protection, as shown and described.

DESCRIPTION

FIG. 1 is a perspective view of the male electrical connector with overload protection of the present invention;

FIG. 2 is a front elevation view thereof;

FIG. 3 is a rear elevation view thereof;

FIG. 4 is a top plan view thereof, the broken lines showing a cord and male prongs are for illustrative purposes only and form no part of the claimed design;

FIG. 5 is a left side elevation view thereof, the right side elevation view is a mirror image; and,

FIG. 6 is a bottom plan view thereof.
